UNITED STATES PATENT OFFICE.

JULIUS PALME, OF NEW YORK, N. Y.

DESIGN FOR A LAMP-SHADE.

SPECIFICATION forming part of Design No. 11,880, dated July 20, 1880.

Application filed February 19, 1880. Term of patent 7 years.

To all whom it may concern:

Be it known that I, JULIUS PALME, of the city, county, and State of New York, have invented a new and original Design for Lamp-Shades, of which the following is a full, clear, and exact description, reference being had to the accompanying drawing, making part of this specification, which represents a vertical central section of a lamp-shade.

The body A of the shade is convex or semi-spherical, and is provided with a trumpet-shaped extension or neck, B, between which and the body is an annular rib, d, and two flat annular shoulders, ee. On the lower part of the body is an annular rib, a, below which is a flat annular flange, b. The body is con-

tracted at s below the lower shoulder e, and the neck B is contracted at x above the upper shoulder.

I claim—

The design for a lamp-shade having the convex body A, trumpet-shaped neck B, rib d, shoulders ee, rib a, flange b, and contracted above and below the shoulders ee, as shown in and by the accompanying drawing. 20 25

In testimony that I claim the foregoing as my invention I have signed it this 14th day of February, 1880.

JULIUS PALME.
